MAIL BOX

Martin Lau, Randolph, Minn.

Application May 26, 1939, Serial No. 275,906

2 Claims. (Cl. 232—17)

My invention has for its primary object the provision of a simple and efficient mail receiving box such as would be especially serviceable for use in reception of mail in rural districts either for delivery to the local owner or mail to be picked up by the rural carrier. However, the box is adapted for various analogous uses or generally for the reception of articles.

Generally stated the invention consists of the novel devices, combination of devices and arrangement of parts hereinafter described and defined in the claims.

More specifically stated the box in its preferred form includes upper and lower box sections supported from a standard and hingedly connected for self closing action under the action of gravity. The arrangement is such that under the action of gravity the box sections will be moved together thereby closing the box and protecting the contents from rain and the weather. By self closing is meant the tendency to close under normal conditions and unrestrained. However, latch means may be provided for temporarily holding the box open for the reception or removal of the mail or other articles.

The preferred embodiment of the invention is illustrated in the accompanying drawing wherein like characters indicate like parts throughout the several views.

30 Referring to the drawing:

Fig. 1 is a perspective showing the improved box, parts of the supporting standard being broken away;

Fig. 2 is a side elevation of the parts shown in Fig. 1, some parts being broken and some parts being sectioned;

Fig. 3 is a fragmentary detail in section taken on the line 3—3 of Fig. 2;

Fig. 4 is a fragmentary detail in perspective showing a portion of the post and yoke of the standard; and

Fig. 5 is a detail with parts sectioned on the line 5—5 of Fig. 1.

The standard shown is made up of a post 6 and a yoke-like extension 7 secured to said post and projecting upwardly therefrom. The post and the yoke may be rigidly connected either by being integrally formed or otherwise.

Working within the yoke 7 is a lower box section 8 and an inverted upper box section 9. The box section 8, relatively near its rear end and at the rear end of its center of gravity, is pivotally connected to the yoke, preferably by trunnions 10 on said box section that work through holes in the yoke. The box sections 8 and 9 are preferably of

the same marginal contour so that they will closely fit together when the box is closed.

At their abutting rear ends the box sections 8 and 9 are pivotally connected preferably by hinges 11. A link 12 is pivotally connected at its rear end to the top of the yoke 7, as shown, by means of a lug 13, and at its free front end said link is pivotally connected to the front end of the upper box section 9, as shown, by means of a lug 14 applied to the top of said box section. 10

The lower box section is shown as provided with a projecting hand piece 15 by means of which its relatively long front end portion may be depressed, thereby opening the box as shown in Fig. 2. However, it is highly important to note 15 that with the box section 9 hung on the link 12, its entire weight will be exerted downward and rearward on the rear end of lower box section 8 through the hinges 11 or like pivotal connection, thereby normally holding the box closed as shown 20 in Fig. 1 under the action of gravity. The weight of the rear end of box section 8 plus the entire weight of upper box section 9 will be much greater than that of the front end portion of said lower box section so that the said automatic closing 25 action will be produced whenever the box sections are released.

It is sometimes desirable to provide a latch means for temporarily holding the box open as shown in Fig. 2; and for the above purpose I have 30 shown the bottom of the lower box section 8 as provided with a light spring latch bar 16 that co-operates with a latch lug 17 secured on the upper end of the post at the bottom of the yoke 7. This latch bar 16 is formed with a pocket 18 that 35 is engageable with the upper end of the latch lug 17 when the box is opened as shown by full lines in Fig. 2. To make the latch lug 17 adjustable, it is mounted in a groove 19 formed in the top of the post 6 and is adapted to be rigidly but adjustably secured as set by a nut-equipped bolt 20 that works through said post and through a slot 21 in said latch lug 17. With the latch provided as shown, it is only necessary to slightly press upward on the hand piece or projection 15 so as to 40 release the latch bar from the said latch lug and thereupon, under the action of gravity, the box will be closed and the parts will assume the position shown in Fig. 1. 45

What I claim is:

1. A box structure of the kind described involving a standard and upper and lower box sections hingedly connected at their rear ends, said standard being extended above and clear of the upper box section, said lower box section being pivoted 50

- to said standard at a point between its top and bottom and between its front and rear ends, and a link pivotally connected to the upper portion of said standard and to the front end of said upper box section and extended above the latter.
5. The structure defined in claim 1 in which

said standard is in the form of a yoke, the top of which extends over the upper box section and to the crown of which said link is pivotally connected, said lower box section being pivotally connected to both sides of said standard.

MARTIN LAU.
